UNITED STATES PATENT OFFICE

JOHN E. HESS, OF NEW WESTMINSTER, BRITISH COLUMBIA, CANADA.

HELICOPTER

Application filed February 9, 1928. Serial No. 253,143.

My invention relates to improvements in helicopters the objects of which are to provide means whereby the machine is capable of rising from a running takeoff or vertically as desired, whereby the machine may function by gliding in a manner substantially similar to an aeroplane of conventional type, or may descend with safety either vertically or in a volplane with its engine stopped.

10 The invention consists essentially of a fuselage which is adapted to be raised by a pair of propellers mounted for rotation about vertical axes, which propellers are concavo convex in cross section and are provided at the trailing edge of each blade with a flap which is adapted to have its rear edge brought into contact with the following blade adjacent its forward edge that the propeller may serve as a parachute, as will be more fully described

15 in the following specification and shown in the accompanying drawings, in which:—

Fig. 1 is a side elevational view of the invention.

Fig. 2 is a front elevational view of the invention.

Fig. 3 is a diagrammatic view showing the position of the horizontal rudders when travelling in different directions.

Fig. 4 is a diagrammatic view showing varying positions of the tail skid and its effect.

Fig. 5 is a diagrammatic view showing the manner of controlling the horizontal rudders.

Fig. 6 is a detail view of the horizontal rudder control levers.

Fig. 7 is a fragmentary view of the propeller blade arrangement and the gap closing flaps.

In the drawings like characters of reference indicate corresponding parts in each figure.

The numeral 1 indicates generally a fuselage having a cockpit 2 and mounted upon a suitable landing gear 3, fitted with wheels 4. The rear end of the fuselage 1 is fitted with a vertical rudder 5 which is controlled from the cockpit 2 in any suitable manner and horizontal rudders numbered 6 and 7, which are mounted respectively at the rear and forward end of the fuselage and are adapted to be controlled by a pair of control

levers generally indicated by the numeral 8 conveniently located in the cockpit, which levers are shown in detail in Figures 5 and 6. The horizontal rudders 6 and 7 are secured to suitably journalled rotatable pivot pins 9 and 10 respectively, which are fitted with sheaves 11 and 12, corresponding sheaves 13 and 14 are freely mounted upon a shaft 15 and endless control wires extend between these sheaves and those of the horizontal rudders, one of said wires numbered 16 being crossed and extending from the sheave 13 to the sheave 11, and the other wire numbered 17 extending as a straight drive from the sheave 14 to the sheave 12, so that when both sheaves 13 and 14 are turned in the same direction, the rudders 6 and 7 will be inclined in opposite directions. The levers 8 consist of two members, one numbered 18 being operatively connected to the sheave 13 and the other numbered 19 being similarly connected to the sheave 14. The upper ends of each of the lever members 18 and 19 are offset as at 20 and are provided with lugs 21 for the purpose of hingingly supporting handles 22 which are held in horizontal position by any suitable spring tension. The inner end of each of the handles 22 passes through an aperture in the upper end of its lever member and terminates with a pronged member 23 so arranged as to interlock when aligned as shown, and to be detached from each other, as shown in dotted line, when either of the handles 22 are depressed, so that when the handles are interlocked the movement of one of them will impart movement through both lever members 18 and 19 to both sheaves 13 and 14 in a single direction and opposed movement to the rudders 6 and 7, but if a similar direction of inclination is required with both horizontal rudders one of the handles 22 may be depressed to disengage it from its fellow and both lever members 18 and 19 be moved in opposite directions.

Secured to the underside of the fuselage 1 is a forked bracket 24 in which a tail skid 25 is pivotally mounted, the forward end of which is fitted with a cable 26 leading over suitable pulleys to a position convenient to

the pilot's seat, that the tail skid may be adjusted to any desired position such as are indicated in Figure 4. Surmounting the fuselage is a plurality of A frames 27 braced together with wires 28 in the usual way, upon which frames a vertical longitudinally disposed fin 29 is carried for the purpose of counteracting any tendency of the machine to side slipping when travelling in bumpy atmosphere and to assist in a similar manner when descending vertically with the propellers stationary.

Extending transversely from the fuselage is a pair of lattice frames 30 each having a vertical member 31 at its outer extremity supporting bearings 32 in which a vertical shaft 33 is mounted. The vertical shafts 33 are adapted to be driven in opposite directions through mitre gears 34 and a pair of aligned transverse shafts 35 which are adapted to be rotated from a suitable motor, not shown, carried within the fuselage. At the upper extremity of each shaft 33 is a propeller 36 which is formed with blades or planes 37 carried upon a suitable spider or frame work 38. The inner end of the planes terminates at an appreciable distance from the axis of the spider 38 so as to provide a central aperture 39. Each plane is concavo convex in cross section and in longitudinal section, the whole of the blades or planes being so disposed as a unit about the vertical axis of the propeller as to be concavo convex also, thus conforming substantially to the contour of a parachute. The planes or blades 37 each have an upper or leading edge 40 and a trailing edge 41, see Figure 7, and to the trailing edge of each is hingedly connected a series of flaps 42 which in normal flight assume an angle parallel to the trailing edge of the plane to which they are attached, as shown in Figures 1 and 2, and are forced into an upward and rearwardly inclined angle on the propeller ceasing to rotate when in flight, as shown in Figure 7, where their trailing edges come into contact with the underside of the next following plane 37 adjacent its forward edge as at 43, thus closing the gap between the upper or leading edge of one plane and the trailing edge of the next preceding plane of the propeller, converting it automatically from a propeller having a vertical lifting effort during rotation into an extended parachute on descending subsequent to the cessation of rotation.

Having thus described the several parts of my invention I will now briefly explain its function.

Prior to rising vertically from the ground the tail skid 25 is set at such an angle as is shown in diagram A in Figure 4, which will dispose the propellers 36 in a horizontal position to direct the air current produced thereby vertically downwards. The air stream will obviously converge as it leaves the pro-

pellers so that a portion of it will strike the rear portion of the forward rudders 7, which would be inclined upwards and forwardly after leaving the ground, so that the air striking it would be deflected rearwardly as shown in diagram E of Figure 3, on a sufficient altitude being reached the rear rudder 6 would be set in a corresponding opposite direction to that of the rudder 7, thus inducing a slight downward tendency at the rear of the machine, which is counteracted by the portion of air flow from the propeller which impinges upon the forward rudder, so that the total air force is directed to maintaining the machine at a substantially constant elevation and to impart to it a forward motion as indicated. If it is desired to rise from a running takeoff, the tail skid 25 is set in the position shown in diagram B of Figure 4, thus disposing the propellers in a forwardly inclined plane, so that the lifting tendency thereof is both upward and forward. On reaching the ground, the tail skid is lowered to the position shown in diagram C of Figure 4, so as to bank the propellers that they may effect a retarding influence to forward travel.

In descending with the propellers stationary, such as in making a forced landing, the horizontal rudders are disposed vertically or at such an angle as to overcome any forward or rearward motion, lateral movement being counteracted by means of the vertical fin 29.

When it is desired to tilt the machine downwards, it suffices to set the forward rudder 7 in a horizontal position and the rearward rudder 6 as shown in diagram F of Figure 3, when some of the lifting effect of the propellers is counteracted by the air stream impinging upon the upper surface of the forward rudder, while the rearward rudder is serving to elevate the rear end of the fuselage 1.

It will be obvious that by providing means whereby the horizontal rudders may be actuated individually or jointly in either direction that any desired effect may be obtained to the pitch of the machine when in flight, so that forward movement may be had, or the machine so adjusted that it will remain without longitudinal movement if desired.

What I claim as my invention is:

1. In a helicopter, a vertical shaft having a propeller concavo convex in cross section and formed with blades spaced apart extending radially from a point remote from the shaft, and flaps hinged to and forming continuations of the trailing edges of said blades, the arrangement being such that the spaces between the blades are closed by upward movement of the flaps when the speed of the propeller is reduced beyond a predetermined point.

2. A helicopter comprising a fuselage, a pair of vertical propellers adapted to be

driven from a source of power, a forward and a rearward horizontal rudder, a lever member for imparting motion to each rudder, and means for connecting said lever members together for simultaneous movement.

5 Dated at Vancouver, B. C., this 30th day of January, 1928.
